UNITED STATES PATENT OFFICE.

SANDFORD C. COX, OF ROCK RAPIDS, IOWA, ASSIGNOR, BY MESNE ASSIGNMENTS, TO COX
MULTI-MAILER COMPANY, OF AUGUSTA, MAINE, A CORPORATION OF MAINE.

ADDRESSING-MACHINE.

No. 870,418

Specification of Letters Patent.

Patented Nov. 5, 1907.

Application filed June 24, 1901. Serial No. 65,806.

To all whom it may concern:

Be it known that I, SANDFORD C. Cox, a citizen of the United States, residing at Rock Rapids, in the county of Lyon and State of Iowa, have invented 5 certain new and useful Improvements in Addressing-Machines, of which the following is a full, clear, and exact specification.

My invention relates more particularly to means for addressing newspapers and similar articles, and it 10 has for its primary object, to provide simple and efficient automatic mechanism for printing the address, or other desired matter, upon the papers, either as they come directly from the press or folding machine, or as they are fed from a special feed box to the printing 15 mechanism; to automatically collect the printed or addressed papers in a compact form, ready for shipment; to automatically deposit markers at certain intervals between the papers, so that the papers which go to one town may be readily distinguished from those 20 which go to another, and to automatically collect the slugs or linotype after they have been utilized for producing the impression, in the same order in which they were originally inserted into the machine.

With these ends in view, my invention consists in 25 certain features of novelty in the construction, combination and arrangement of parts, by which the said objects, and certain other objects hereinafter appearing, are attained, all as fully described with reference to the accompanying drawings, and more particularly 30 pointed out in the claims.

In the said drawings—Figure 1, is a side elevation of my improved addressing machine, partly broken away and partly in vertical section; Fig. 2 is a plan view thereof; Fig. 3, is a side elevation, looking at 35 the opposite side to that presented in Fig. 1; Fig. 4 is a vertical, longitudinal, sectional view, taken on the line 4—4, Fig. 2; Fig. 4^a is a detail vertical sectional view of the lower edge of the follower-board, showing the attaching hook. Fig. 4^b is an enlarged 40 detail sectional view taken transversely of the type wheel, and a slug therein, showing means whereby the notched or differently-proportioned slugs are utilized for actuating the means for designating one batch of papers from another. Fig. 5 is an enlarged vertical 45 sectional view of the type wheel, slug retaining belt, and slug-race or galley; Fig. 6 is a front elevation thereof; Fig. 7, is a side elevation thereof, showing the slug receiving chute and galley, partly in vertical section, with the pusher withdrawn; Fig. 8, is a similar view, 50 showing the pusher advanced; Fig. 9, is an enlarged vertical, longitudinal sectional view of the feed box, showing the feeder and the paper carrying tapes in elevation; also, illustrating the paper stops or gages, and a part of the typewheel; Fig. 10 is a similar view, 55 showing the feeder in the act of advancing a paper

between the carrying tapes; Fig. 11, is an enlarged detail sectional view of the needle block, hereinafter described; Fig. 12, is a detail longitudinal sectional view of the paper receiving receptacle; Fig. 13, is a similar view, showing the packer advanced; Fig. 14, 60 is a plan view thereof; Fig. 15, is a detail side elevation of the type-wheel and impression roll, showing the parts in the act of producing an impression on a paper; Fig. 16, is a similar view, showing the paper advancing, with the impression thereon; Fig. 17 is an 65 edge view thereof; Fig. 18, is a vertical, transverse, sectional view of a modified form of type-wheel, hereinafter described and Fig. 19 is a front elevation or face view thereof.

1, is a frame or stand of any suitable form and construction, upon which all of the working parts are supported. 70

When the apparatus is used for addressing newspapers and other articles that have already been collected in bulk after leaving the press, a feed-box, 2, of any suitable 75 construction is employed, for receiving the papers as they come from the delivery of the press. In the example of the invention shown in the drawings, this feed-box is of elongated, trough-like form, supported 80 on the frame, 1, in an inclined position, by means of standards, 3; and in the bottom of the box, 2, is arranged suitable mechanism for advancing the papers, 5, towards the lower end thereof, as the papers are fed therefrom, one at a time, by the mechanism which will presently be described. As shown in the drawings, this device in the bottom of the box, 2, consists 85 of an endless belt or carrier, 6, running over a suitable roller, 7, at each end of the box, 2, and having a series of perforations or eyelets, 8 (see Fig. 2), into which may be engaged a finger or hook, 9, secured in any 90 suitable manner to an inclined follower board, 10, supported in the box, 2. The upper end of this follower board is provided at each side with a laterally projecting pin, 11, which rests upon the edge of the box, 2, and thus holds the board in an inclined position. The 95 lower end or edge of the board, 10, is provided with a coiled spring, 12, which engages against a shoulder, 13, on the board, and a lug, 14, on the finger, 9, thus tending to force the finger, 9, downwardly, and hold it in the eyelets, 8. The finger, 9, is formed on the lower 100 end of a pull-rod, 15, which is secured to the board, 10, by suitable keepers, 16, so that, by pulling upwardly upon rod, 15, the finger, 9, may be disengaged, and the board advanced or retracted to accommodate the papers in the box, 2. 105

The lower one of the rollers, 7, is driven continuously at the requisite rate of speed, by means of a bevel-gear, 17 (see Fig. 1), meshing with a companion gear, 18, on the upper end of a short shaft, 19, which is in turn geared to a horizontal shaft, 20, by means of a 110

pair of bevel gears, 21. The shaft, 20, derives motion from a type-wheel or cylinder, 22, having a bevel gear, 23, on the side thereof, meshing with a bevel pinion, 24, on shaft 20, or any other suitable means, whereby belt, 6, driven in unison with type-wheel 22, may be employed.

Arranged at the lower end of the feed-box, 2, are two series of upper and lower tapes, 25—26, the former of which at one end pass over an idle roller 27, arranged 10 adjacent to the lower end of box 2, while at the other end they pass over a roller, 28, journaled in a suitable bearing, 29, on the frame, 1, and in passing over roller 28, their lower folds turn downwardly over a press, against the upper folds of tapes 26, where the latter 15 pass over a roll 30, journaled in bearing 29, and geared to roll 28 by pinions, 31, one of which latter meshes with, and derives motion from, a large gear-wheel, 32, secured to shaft 33, projecting across the frame and carrying at its opposite end a large gear, 34, which 20 meshes with a pinion 35, on driving shaft 36, carrying belt pulley 37. The ends of the lower tapes, 26, removed from roller 30, pass around a roller 38, having its trunnions 39 journaled in the ends of a pair of horizontal arms or levers, 40, and also engaging in slots 41, 25 formed in the lower arms, 42, of two bell-crank levers, suitably pivoted upon opposite sides of the lower end of the feed-box 2, and having their upper arms, 43, pivoted respectively to two links, 44, which are in turn connected to a sliding bar, 45, arranged in guide 30 slots, 46, formed in opposite sides of the feed-box 2, said sliding bar 45 having pivotal connection with the upper end of an arm, 47, whose lower end is pivoted to a feed-block, 48, having its engaging surface provided with a series of needles, 49, adapted to engage the papers, 5, in the feed-box, one at a time, and advance them to a position between the upper and lower tapes, 25—26, in the manner shown in Figs. 9 and 10, as the bell-cranks, 42—43 are oscillated; and this oscillation is accomplished by the up and down movement of 40 levers or arms, 40. As the arms 40 descend, they cause the lower tapes, 26, to separate from the upper tapes, 25, in the manner shown in Fig. 10, so as to admit the paper, 5, between them, and at the same time they induce a feed movement of the paper by carrying the 45 feed blocks 48 downwardly and outwardly, the outward movement being due to the inclined position of the papers in the feed box. The opposite ends of these arms, 40, are provided with stops or gages, 50, projecting upwardly between the upper folds of the 50 lower tapes, 26, in such a manner that, as the papers, 5, are advanced by the tapes which run continuously, the stops or gages, 50, will arrest the paper between the tapes while the latter continue to move, a sufficient length of time to permit the impression mechanism, hereinafter described, to produce the impression. By this means, it will be seen that as the arms 55 40 descend at one end for admitting one paper, they rise at the other end for arresting the paper previously admitted, and as their gages, 50, descend to permit the impression or the addressed paper to pass on, the opposite ends of the arms rise for closing the tapes together against the paper which has just been admitted between them.

The arms, 40, as shown in Fig. 2, are brought together 60 at their mid-length, and pivotally supported on a pin,

51, which passes through the upper ends of suitable standards, 52^X, mounted on main frame, 1, said arms 40 being suitably keyed or secured to pin 51, so that the oscillation of one of the arms will be imparted to the other. The arms are given the necessary oscillatory or 70 up and down movement, by means of a cam, 52, secured to or formed on the side of the type-wheel, 22, as better shown in Figs. 3, 4, 9 and 10, which cam is constituted by a tortuous groove formed in the side of the type-wheel, 22, and into which groove projects a 75 pin or lug, 53, extending from the side of a hanger, 54, formed on one of the arms 40, so that, as the type-wheel 22 revolves, the arms will be oscillated in the described manner.

As shown more clearly in Fig. 5, the type-wheel, 22, 80 is provided with a series of peripheral pockets, 55, of sufficient size to receive a single slug or linotype, 56, leaving the upper edge of the slug protrude sufficiently to enable it to print when forced into engagement with any suitable platen, which will be presently described, 85 and the waves or corrugations of the cam groove, 52, are equal in number to the pockets, 55, in the type-wheel 22, so that at each impression, the arms, 40, will be lowered, and the paper which has just been printed will be carried out of the way by the tapes 25—26, and 90 another paper fed in between said tapes. The impression is produced by an impression roller, 57, arranged above the type-wheel 22 in such a position that, if forced downwardly, at the proper time, it will press the paper, 5, against the slug, 56, and produce the impression on the under side of the paper, and when raised will permit the paper to pass, the stops or gages 50 at that time being lowered. The impression roller, 57, is mounted in a bracket, 58, secured to or formed on a slide, 59, mounted in vertical ways, 60, and normally 100 pulled downwardly by a spring, 61, secured to the under side of slide 59 at one end, and to a bolt, 62, at the other end, which serves to secure the ways, 60, to the main frame, 1. The impression roller, 57, is lifted out of engagement to permit the paper to pass at the 105 proper time, by means of a cam, 63, formed on or secured to the side of the type-wheel, 22, and having a number of waves or depressions, as shown in Figs. 15 and 16, equal to the number of pockets, 55, employed in the type-wheel; so that, as each of the slugs arrives 110 at the upper position directly under the impression roller, 57, a pin or lug 64, projecting from a depending arm or bracket, 65^X, or slide 59, will drop into one of the notches of cam 63, and permit 61 to pull impression roller 57 down against the top of the paper, and force 115 the latter against the printing surface of the slug, and as the type-wheel continues to revolve, cam 63 lifts pin 64 and relieves the pressure of impression roller 57. The extent of the impression may be governed or regulated by a set-screw, 65, threaded in cross-bar 66, on 120 ways 60, and impinging the under side of slide 59.

Type-wheel 22 is keyed or otherwise secured to the shaft, 33, and is therefore continuously revolved at the requisite rate of speed by pinion 35 on the main driving shaft 36.

Arranged adjacent to typewheel 22, is a galley or race, 67, for holding a supply of the slugs, 56, as better shown in Fig. 5, and the discharge end of this galley has an incline, 68, which is so arranged that when a slug is advanced to the incline, it will drop lower-end-fore- 130

most, into one of the pockets, 55, of the type-wheel, which is so timed with reference to the dropping of said slug that the slugs will descend into said pockets one at a time as the wheel revolves. In order, however, that 5 the slug may enter the pocket with greater certainty and automatically find a proper sitting therein, one side of the pocket, the uppermost side, is cut away on an oblique angle, as shown at 55^a, the other side of the pocket being formed on a line radiating from the center 10 of the wheel, and the lower or inner end of the pocket being made to conform to the slug, so that after the slug enters, it will be held from tipping laterally. The galley or race, 67, is provided with means for advancing the entire supply of slugs there-along, with the requisite 15 degree of speed, for thus dropping them one at a time into the pockets, 55, and this means preferably consists of an endless belt or conveyer, 69, one end of which passes around an idler, 70, mounted at the back of the machine in bracket 71, while the other end passes 20 around driving roller 72, secured to shaft 73, which is journaled in a bracket, 74, and provided with a worm-wheel, 75, meshing with a worm, 76, on shaft 20 before described, so that the motion of the type-wheel will be imparted to the belt or conveyer, 69, through the intermediary 25 of said shaft, the parts being so proportioned and timed that one of the slugs will arrive at the top of the incline, 68, just as one of the pockets, 55, arrives at a position approximately under the lower end of said incline, the top of galley or race, 67, just above incline 30 68, being provided with a cross-stop, 77, for preventing the slug from plunging head-foremost, when it reaches the incline.

As the type-wheel, 22, continues to revolve, the printing having been effected from each of the slugs as it arrives at the top of the wheel, the slugs are discharged 35 from the pockets, 55, one at a time, into a slug chute, 78, arranged under the type-wheel, approximately in line with the vertical diameter thereof, and in order that the slugs may not fall out prematurely, a flexible 40 shield or retainer is carried around the lower side of the type-wheel from the chute, 78, upwardly. This retaining device consists of a belt, 79, composed of canvas, cloth, rubber, leather, or any other more or less yielding, flexible material, passes around three rollers, 45 80, 81, 82, in such a manner that the belt is made to conform to the periphery of the type-wheel and hold the slugs in place; the rollers being idlers, the belt is permitted freedom of movement with the wheel, and thus undue rubbing or friction against the surfaces of the 50 slugs may, if desired, be avoided, or by increasing such friction, it may be utilized for cleaning the faces of the types. The lower roller, 82, is made of rubber or other elastic material, so that no injury will be done to the type surface. The upper end of this chute, 78, is as 55 wide as the slug is long, as shown in Fig. 6, and one side of the chute is provided with a cross-pin, 83, arranged to be struck by one end of the slug as it descends, for turning the slug up on end in the position shown in dotted lines in Fig. 6, and thus causing it to descend 60 on end and avoid damage to its printing surface, the lower end of the chute, 78, being narrower than the upper end, so as to hold the slug from again falling down into a horizontal position. As the slug rests on end at the bottom of chute 78, it is pushed along into a horizontal galley 84, by means of a pusher, 85, adapted to

project through a suitable aperture, 86, in the back of chute 78, and this pusher, 85, is inclined, as better shown in Figs. 7 and 8, so that it will keep the entire body of slugs in an inclined position, as illustrated in said figures, and thus avoid the possibility of the slugs 70 tilting backwardly in the horizontal chute and clog up the latter. The galley, 84, is gradually twisted into a horizontal position towards its outer end, as better shown in Figs. 1 and 4, so that as the slugs are advanced therealong, they will finally arrive into a position right 75 side up and in their regular order, just as they were when placed in the galley or race, 67, originally, and may be removed from galley 84 into any suitable receptacle, and placed back in the feed galley or race, 67.

The pusher, 85, is reciprocated back and forth to perform its described function in unison with the movement of type-wheel 22, so that as each slug prints, one slug will drop, and that slug will be advanced against the main body of slugs in the discharge galley, 84, as shown in Fig. 8, and the pusher 85 will recede out of galley 78, to avoid interfering with the next descending slug. This operative connection between pusher 85 and the type-wheel, is shown in Figs. 7 and 8, as consisting of a lever, 87, pivoted on a pin, 88, secured in any suitable support on the main frame, the lower 90 end of said lever being forked and straddled over a reduced portion, 89, of stem, 90, which carries pusher 85, said stem being mounted to slide in suitable standards, 91, while the upper end of said lever, 87, is provided with a lateral pin, 92, engaging in the aforesaid waving 95 groove or cam 52, which causes said lever 87 to oscillate, once for each impression.

The printing surfaces of the slugs, 56, are inked while advancing along galley or race 67, by any suitable means. In the example of the invention shown in the drawings, an inking roller, 93, is employed for this purpose. The surface of the roller is arranged to impinge the surfaces of the slugs between the sides of the race, 67, but the trunnions of the roller ride along inclined tracks, 94, on the sides of race 67, which, as the roller 100 moves back and forth, carries the surface thereof first into engagement with the slugs, and then into engagement with a pair of fountain rollers or distributing rollers, 95, of the usual or any suitable form, mounted in standards, 96, one of said rollers being provided with a 105 pulley, 97, connected by belt 98, to a driving pulley 99, on shaft 33. The trunnions of roller 93 are mounted in slots, 100, in the upper ends of arms 102, which are secured to a cross-shaft, 103, whereby they will oscillate in unison for carrying the inking roller, 93, back 110 and forth.

The shaft, 103, is provided at its mid-length with a fork, 104, which is engaged by a cam or crazy wheel, 105, on one end of a longitudinal shaft, 106, whose other end is provided with a worm-wheel, 107, engaging with 120 a worm, 108, on shaft 33, so that as the type-wheel revolves, the arms 102 will be thrown back and forth for inking the type.

After the papers are addressed, they are collected together in any suitable receptacle, and where the 125 papers thus addressed are intended for different towns or localities, those belonging to one town are separated from those belonging to another by the interposition of a card or marker. The mechanism for accomplishing this will now be described. After 130

the paper leaves the impression devices, it is carried by the tapes 25, 26, in a downward direction, between the two rolls 28—30, and is discharged into a packing receptacle, 109 (see Fig. 4), into which the paper falls 5 on edge, and as it does so, it is advanced along the receptacle 109 by a reciprocating packer, 110, which recedes into the back end of the receptacle until the paper drops, and then advances for pushing the paper forward, any suitable object, 111, being located in the 10 box or receptacle, 109, in advance of the papers, for holding them upright on one side when the pressure of the packer, 110, is removed, while they are held on the other side by laterally projecting cleats, 112, secured to the sides of box 109, and beyond which they 15 are pushed each time by the packer, 110. The packer, 110, is secured to a stem, 113, supported by any suitable guide, 114, and connected by a pitman, 115, to a crank, 116, to the shaft 36, thus giving the packer, 110, an advancing movement often enough for pushing the 20 papers forward as they collect in the back end of box 109, the number of strokes of the packer with relation to the number of impressions being, of course, governed by the relative proportions of gear 34 and pinion 35.

Arranged just below shaft 33 is a holder, 117, for a 25 store of markers or cards, 118, upon which may be printed the name of the various towns to which the papers are to be sent, and these cards are adapted to be dropped into the box, 109, at stated intervals, or between the entire supply of papers for one town and 30 the next supply for another town, and to this end the holder, 117, is so arranged that, when the markers, 118, are advanced a sufficient distance, they will fall, one at a time, therefrom, onto an incline, 119, leading downwardly to box 109, from holder 117, the upper side of 35 holder 117 being provided with cross-stop 120, for keeping the markers on edge. The markers are advanced along the holder, 117, with the requisite speed by means of a feeder or follower, 121, projecting upwardly through a slot, 122, in the bottom of the 40 holder, and engaging the markers, the lower end of follower 121, having a nut, 123, threaded on screw, 124, which is driven by a pair of bevel gears, 125, from a vertical shaft, 126, which in turn is driven by gears, 127, from a horizontal shaft, 128, and this in turn is 45 connected by a pair of bevel gears, 129, to an upright shaft, 130, on whose upper end is a pin wheel, 131.

The pins of this wheel, 131, project through an annular groove, 132, cut in the side of type-wheel, 22, and of sufficient depth to enable the pins of pin-wheel 131 to 50 project into engagement with slugs 56, and to be rotated thereby as type-wheel 22 revolves, and thereby impart motion to the follower or feeder, 121, and advance the entire supply of markers, 117, sufficiently to cause one of them to drop into box 109. In order that the 55 follower, 121, may be actuated at such time only as the last one of the entire supply of papers for any one community has fallen into box 109, the slugs, 56, for the subscribers of that entire community, are all, with the exception of the first one, provided in one end 60 with a slot or notch, 133, so that all of said slugs will pass pin-wheel, 131, without actuating it; but when the first slug of the next series arrives at said pin-wheel, it will strike and actuate the wheel, and thus throw down into box 109 one of the markers 118, and 65 thereby partition off the supplies for the two com-

munities, or, if desired, all of the slugs excepting the last one of each series, may be provided with said slot 133, or otherwise differently shaped from said last slug, so as to pass the pin-wheel without actuating it.

In the modification shown in Figs. 18 and 19, the 70 type-wheel indicated at 22^a, is of considerable smaller diameter than the form first described, and has fewer pockets, but is adapted to be rotated at a much higher rate of speed. These pockets are formed, as shown in the drawing, with their sides cut away from one pocket 75 to the other, as indicated at 22^b, leaving only a sufficient part of the cylindrical surface of the type-wheel at 22^b, to engage the paper and pinch it against the platen roller, 57, and thus constitute a stop for engaging and holding the paper while it is being printed. With 80 this form of wheel, the paper stops or gages, 50, on the arms 40, will be unnecessary. As soon as the cut-away part of the type-wheel turns uppermost under platen roller 57, the pressure on the paper will be released and the rapidly moving tapes, 25—26, will carry it out 85 of the way, and the next paper will be advanced into position by the tapes in time to be caught and pinched by the platen roller and surface 22^b of the type-wheel.

Having thus described my invention, what I claim 90 as new therein and desire to secure by Letters-Patent, 95 is:

1. In an addressing machine, the combination of a gallery or race for containing slugs, a type-wheel or cylinder, having slug pockets arranged adjacent to the end of said race, a continuous movable bottom for feeding the slugs 95 from said race into said pockets, an incline or chute at the discharge end of said bottom, a platen, means for forcing said platen towards said type-wheel, and means co-operatively connecting said platen and type-wheel together, substantially as set forth.

2. In an addressing machine, the combination of a gallery or race for containing slugs, a movable bottom member on which the slugs rest and by which they are fed along said race, a type-wheel or cylinder having slug 100 pockets arranged adjacent to said race, and a platen co-operatively related to said type-wheel for producing the impression, substantially as set forth.

3. In an addressing machine, the combination of a gallery or race for containing slugs, a continuous belt arranged in the bottom of said race and constituting a movable support for feeding said slugs therealong, a type-wheel or cylinder having slug pockets arranged adjacent to the end of said race, and a platen co-operatively related to 110 said type-wheel, for producing the impression, substantially as set forth.

4. In an addressing machine, the combination of a gallery or race for containing slugs, having an incline or chute at its discharge end, and a cross-stop over said chute for engaging the upper edge of the slug when the latter arrives at the chute, a type-wheel having pockets arranged 120 adjacent to the end of said chute, for receiving said slugs, and a platen co-operatively related to said type-wheel, for producing the impression, substantially as set forth.

5. In an addressing machine, the combination of a gallery or race for containing slugs, a traveling belt in the bottom of said race for feeding the slugs therealong, a type-wheel or cylinder having pockets for receiving said slugs from said race, geared to, and operating in unison with, said belt, and a platen co-operatively related to 130 said type-wheel, substantially as set forth.

6. In an addressing machine, the combination of a gallery or race for slugs, a type-wheel arranged adjacent thereto and having pockets for receiving the slugs therefrom, cut away or oblique on one side and radial on the other side, whereby the slugs will readily drop into said pockets, and afterwards be held in a radial position with reference to said wheel, and a platen co-operatively related to said wheel, for producing the impression from said slugs, substantially as set forth.

7. In an addressing machine, the combination of a galley or race for slugs, a type-wheel arranged adjacent thereto and having pockets for receiving the slugs therefrom, each having its bottom formed to fit the edge of the 80
5 slug, and one of its side walls cut away on an oblique angle, said cut-away side being presented upwardly to the discharge end of the race, and means for producing the impression from the slugs while in said wheel, substantially as set forth.
10. In an addressing machine, the combination of a galley or race for slugs, a type-wheel having pockets for said slugs, means for feeding the slugs from said galley into said pockets, an impression device, and means for intermittently oscillating the said impression device towards 85
15 and from the type-wheel, for pinching the paper between it and said type-wheel, substantially as set forth.
9. In an addressing machine, the combination of a galley or race for slugs, a type-wheel having pockets for receiving the slugs therefrom, means for feeding the slugs 90
20 from said galley into said pockets, an idle impression roll, and means for intermittently oscillating said roll for pinching the paper between it and said type-wheel, substantially as set forth.
10. In an addressing machine, the combination of a galley or race for slugs, a type-wheel having pockets for receiving the slugs therefrom, means for feeding said slugs from said galley into said pockets, an impression device, a 95
25 spring for pressing said device towards said type-wheel for producing the impression, and means for forcing it away from said wheel to allow the paper to pass, substantially as set forth.
11. In an addressing machine, the combination of a galley or race for slugs, a type-wheel having pockets for receiving the slugs therefrom, an impression device located 100
30 adjacent to said type-wheel, means for forcing said device in one direction with reference to said wheel, and a cam having waves corresponding in number to the number of pockets in said wheel, for forcing said device in the opposite direction, substantially as set forth.
40. 12. In an addressing machine, the combination of a galley or race for slugs, a type-wheel having pockets for receiving the slugs therefrom, an impression device located adjacent to said wheel, means for forcing said device in one direction with reference to the wheel, and a cam carried by said wheel and having waves corresponding in 105
45 number to the number of pockets in said wheel, for forcing said device in the opposite direction as each slug passes it, substantially as set forth.
13. In an addressing machine, the combination of a 110
50 type-wheel having pockets for holding slugs, an impression device co-operatively related thereto, a chute for said slugs arranged under said wheel for catching them, and a flexible band extending around a part of the lower side of said wheel from said chute upward, substantially as set forth.
14. In an addressing machine, the combination of a 115
55 type-wheel having pockets for receiving and holding slugs, an impression device co-operatively related thereto, a chute for receiving said slugs as they fall from said type-wheel, said chute being as wide at the top as the length of the slug, and of less width at the bottom, whereby the slug will be turned on end as it falls from the wheel, substantially as set forth.
15. In an addressing machine, the combination of a 120
60 type-wheel having pockets for receiving and holding slugs, an impression device co-operatively related thereto, a chute for said slugs arranged under said wheel for catching them as they fall therefrom, and means in said chute for turning the slugs on end as they fall, substantially as set forth.
16. In an addressing machine, the combination of a 125
65 type-wheel having pockets for receiving and holding slugs, an impression device co-operatively related thereto, a chute for said slugs, arranged under the wheel, for catching them as they fall therefrom, the upper end of said chute being as wide as the length of the slug, and the pin extending across one side of said chute for engaging one end of the slug and turning it up on end as it falls into the chute, substantially as set forth.
17. In an addressing machine, the combination of a 130
70 type-wheel having pockets for receiving and holding slugs, an impression device co-operatively related thereto, a chute arranged under the lower side of said wheel for catching the slugs as they fall therefrom, means in said chute for turning the slugs on end, and a twisted horizontal galley extending from the lower end of said chute, for receiving the slugs and turning them right side up, substantially as set forth.
18. In an addressing machine, the combination of a 135
75 type-wheel having pockets for receiving and holding slugs, an impression device co-operatively related thereto, a chute arranged under said wheel for receiving the slugs as they fall therefrom, and an elastic band extending around a part of the lower side of the wheel from said chute upwardly, for holding the slugs in place in the wheel until the chute is reached, substantially as set forth.
19. In an addressing machine, the combination of a 140
80 type-wheel having pockets for receiving and holding slugs, an impression device co-operatively related thereto, a chute arranged under said wheel, for receiving the slugs as they fall therefrom, a band arranged around the lower side of said wheel for holding the slugs in place until said chute is reached, and an elastic roller, over which the lower end of said band runs, and against which the slugs impinge as they approach the chute, substantially as set forth.
20. In an addressing machine, the combination of a 145
85 type-wheel having pockets for receiving and holding slugs, an impression device co-operatively related thereto, a chute arranged under said wheel for receiving the slugs as they drop therefrom, a horizontal galley for receiving the slugs from said chute, a reciprocating pusher for advancing the slugs along said galley, and a cam, actuated in unison with said type-wheel, and having waves equal in number to the pockets therein for operating said pusher, substantially as set forth.
21. In an addressing machine, the combination of means for printing the address on the papers, means for collecting the papers together after the address is printed 150
90 thereon, and means for depositing markers between the papers at stated intervals, substantially as set forth.
22. In an addressing machine, the combination of means for printing the address upon the papers, means for collecting the papers together thereafter, and means for depositing markers between the papers at stated intervals, timed with, and co-operatively related to, said addressing means, substantially as set forth.
23. In an addressing machine, the combination of means for printing the addresses upon the papers, a package receptacle for the addressed papers, means for depositing the papers in said receptacle, and means for depositing a marker in said receptacle between the papers at stated intervals, substantially as set forth.
24. In an addressing machine, the combination of 155
95 means for printing the addresses upon the papers, a package receptacle for the addressed papers, means for depositing the papers in said receptacle, a holder for a number of markers or cards, arranged to discharge into said receptacle, a feeder for advancing said markers along said holder, and means connecting said feeder with said addressing means, substantially as set forth.
25. In an addressing machine, the combination of a type-wheel adapted to carry a number of slugs, means for printing the papers from the slugs therein, means for collecting the printed papers together, and means actuated by the slugs in said wheel, for depositing markers between the papers at stated intervals, substantially as set forth.
26. In an addressing machine, the combination of means for advancing a plurality of differently shaped slugs, and producing impressions therefrom, means for collecting the printed papers together, and means actuated by the slugs of a certain shape, for depositing markers between the papers at stated intervals, substantially as set forth.
27. In an addressing machine, the combination of means for advancing a plurality of differently shaped slugs, means for producing impressions therefrom, means for collecting the impressions together, a holder for a plu-

- rality of marker cards, a follower for advancing said cards along said holder, a screw for advancing said follower, and a pin-wheel for operating the said screw, arranged to be operated by the slugs of a certain shape, substantially as set forth. 5
28. In an addressing machine, the combination of a type-wheel having pockets therein for receiving and holding slugs of different shapes, means for producing impressions from said slugs while in said wheel, means for collecting said impressions together, a holder for a plurality of markers arranged to discharge the same between said impressions, means for advancing said markers along said holder, and a pin-wheel arranged adjacent to said type-wheel, and adapted to be struck and operated by the slugs of a certain shape therein, and means operatively connecting said pin-wheel with said means for advancing the markers along said holder, substantially as set forth. 10
29. In an addressing machine, the combination of a type-wheel having a number of pockets for receiving and holding slugs, an impression device co-operatively related to said type-wheel, upper and lower tapes for advancing the papers between said type-wheel and impression devices, stops or gages projecting between said tapes for arresting the movement of the papers, and a cam co-operatively related to said stops or gages, and having waves equal in number to said pockets, for disengaging said gages at each impression, substantially as set forth. 15
30. In an addressing machine, the combination of means for producing an impression, means for holding a store of papers, means for carrying the papers from said store to said impression means, a gage or stop for arresting the papers between said impression means, means for disengaging said gage or stop at each impression, a needle block for engaging the papers, one at a time, in said store, and levers connecting said block with said gage or stop, for actuating the block at each impression to feed a paper to said carrying means, substantially as set forth. 20
31. In an addressing machine, the combination of a feed box for holding a store of papers, an endless belt arranged in the bottom thereof and provided with eyelets, a follower arranged in said box and connected with said belt, and means for feeding the papers from said box, co-operatively connected with said belt, substantially as set forth. 25
32. In an addressing machine, the combination of a gallery or race for containing slugs, a continuous belt having a plain upper surface arranged in the bottom of said race and constituting a movable support for feeding said slugs along the race, and impression devices arranged at the end of the race for producing impressions from the slugs successively as they are fed forward by said belt. 30
33. In an addressing machine, the combination of a gallery or race for containing slugs, impression devices arranged at the end of said race for producing impressions from the said slugs successively, a member movable towards said impression devices, arranged in the race and having a plain friction surface against which the slugs bear, and means for moving said member towards said printing devices independently of the slugs. 35
34. In an addressing machine, the combination of a gallery or race for containing slugs, a tape or band arranged in the bottom of the race and supported throughout its length, whereby it will not sag, and having a plain surface constituting a support for the slugs in the race, impression devices arranged at the end of the race for producing impressions from the slugs successively, and means for moving said tape or band towards said impression devices. 40
35. In an addressing machine for addressing papers and the like, the combination of a hopper or box for containing a store of papers to be addressed, means for holding the papers inclined in said hopper, means for feeding the store forward as a whole, needle-blocks for engaging and feeding the papers from the hopper singly, pivoted arms to which said needle-blocks have pivotal connection, means for operating said arms in unison to move said blocks in an inclined plane, and means for applying the address to the papers thus fed outwardly by the needle-blocks. 45
36. In an addressing machine, the combination of a feed box for holding a store of papers, an endless belt arranged in the bottom thereof and provided with eyelets, a follower arranged in the box, a spring controlled finger carried by the follower and adapted to engage the eyelets, means for disengaging said finger, means for moving the belt, and means operatively related to the belt for feeding the papers from the box. 50
37. In an addressing machine, the combination of a feed box for holding a store of papers, a slide moving at the forward end of the box, an arm pivoted at one end to the slide, a needle block pivoted to the free end of the arm and adapted to engage the paper, a pivoted lever, a connection between the lever and the slide, and means for rocking the lever to move the slide for causing the block to feed the papers. 55
38. In a paper-addressing machine, the combination of means for putting the address on the papers, embodying notched and unnotched disconnected slugs bearing the matter to be printed on the papers, and means for holding and carrying the slugs while the impression is being made therefrom, means for collecting the papers together after they are addressed, and means arranged to engage in the notches of said slugs, and to be engaged by the unnotched slugs for designating one batch of the addressed papers from another. 60
39. In an addressing machine, the combination of a plurality of notched and unnotched slugs disconnected from each other, a rotary type-wheel having pockets or holders for carrying said slugs while being printed from, means for collecting the addressed papers together, and means for distinguishing some of said papers from others after they are addressed, embodying a member arranged contiguous to said type-wheel so as to run in the notched slugs and be engaged and actuated by the unnotched slugs. 65
40. In an addressing machine for addressing papers and the like, the combination of a hopper or box for containing a store of papers to be addressed, means for feeding the store forward as a whole, a pivoted support, a needle block pivoted to the support and means for moving the support to bodily move the block downwardly in a plane parallel with the plane of the papers to feed the said papers. 70
41. In an addressing machine for addressing papers and the like, the combination of a hopper or box for containing a store of papers to be addressed, means for holding the papers inclined in said hopper, means for feeding the store forward as a whole, pivotally supported needle blocks, and means for bodily moving the needle blocks downwardly in an inclined plane to feed the papers. 75
42. In an addressing machine for addressing papers and the like, the combination of a hopper or box for containing a store of papers to be addressed, means for holding the papers inclined in said hopper, means for feeding the store forward as a whole, a pivoted support, a needle block pivotally connected to the support, and means for moving the support to bodily move the needle block downwardly in an inclined plane to feed the papers. 80
43. In an addressing machine for addressing papers and the like, the combination of a hopper or box for containing a store of papers to be addressed, means for holding the papers inclined in said hopper, means for feeding the store forward as a whole, a pivoted support, a needle block pivotally connected to the support, means for bodily moving the support and the needle block to cause the latter to move downwardly in an inclined plane to feed the papers, and means for applying the addresses to the papers thus fed by the needle blocks. 85
